ILLUMINABLE DISPLAY SIGN

Conrad J. Escalante, Los Alamitos, Calif.
(1251 W. Gaylord St., Long Beach 13, Calif.)

Filed Oct. 29, 1962, Ser. No. 72,302

Term of patent 14 years

(Cl. D1—12)

FIG. 1 is a front perspective view taken from one side of an illuminable display sign embodying my new design, the opposite side being a mirror image of the side shown;

FIG. 2 is an elevational view thereof taken from the side shown in FIG. 1, the fragmentary broken line showing of a larger sign being for purposes of illustration only;

FIG. 3 is a top plan view of said sign;

FIG. 4 is a rear elevational view of said sign; and

FIG. 5 is a bottom plan view of said sign.

The dominant features of my new design reside in those portions shown in full lines.

I claim:

The ornamental design for an illuminable display sign, substantially as shown and described.
